GALVANOMETER MOVABLE COIL SUPPORT

Marvin E. Morrow, Tulsa, Okla., assignor to Century Geophysical Corporation, Tulsa, Okla., a corporation of Delaware

Application August 20, 1945, Serial No. 611,647

13 Claims. (Cl. 171—95)

1

The present invention relates to improvements in oscillograph galvanometers, such as are used in seismograph oscillograph cameras and the like. In these instruments as many as 25 to 36 separate D'Arsonval type galvanometers are required to record the outputs of as many channels of amplifier on a single moving sheet of photographically sensitive paper or film. It is imperative that the separate galvanometers of the bank be of small size in order to accommodate the large number of units in the limited space of the camera. It is also imperative that extremely high sensitivity be employed in these units because of the fact that they are used almost exclusively in field operations and the amount of power available for useful gain in the amplifiers is limited. Furthermore, all channels of recording must be identical in response and therefore, the design of the galvanometers must be such as to permit the exact matching of units in frequency, damping and sensitivity.

Because of the very small dimensions necessarily required for such galvanometers and their constituent parts, considerable difficulty is experienced normally in assembling the vibratory elements in their enclosing barrels and adjusting the several parts to attain the desired degree of matching of the units in their frequency, damping and sensitivity characteristics. This is particularly true in the case of high frequency galvanometers, having a high degree of electrical damping. To increase the maximum frequency and degree of damping, pole piece inserts are normally installed in the enclosing barrel in order to reduce the air gap to the maximum degree and thereby increase the flux density. This, however, further increases the difficulties of construction and assembly of the galvanometer since it necessarily reduces the dimensions of those portions of the vibratory element and its anchoring members which are required to pass between the pole piece inserts when being introduced into the barrel.

Furthermore, in the prior art galvanometers, once the assembly within the barrel has been completed, and the vibratory element connected to its anchoring members and locked in the barrel, the vibratory element cannot normally be removed without substantial damage thereto or without at least substantially altering the previous adjustments. This is because the anchoring members are normally so constructed as to require their removal from the barrel separately and apart from the vibratory element connected thereto.

2

It has been found that the many advantages of the barrel type galvanometer can best be attained if the galvanometer assembly can be set up, adjusted and tested in final form before being placed inside the barrel. This can be done only if the entire assembly, or the major portion thereof, can be inserted and withdrawn from the barrel at any time without affecting its operation in the least and with a minimum amount of adjustment of the vibratory element once it has been inserted in the barrel.

Accordingly, it is a principal object of this invention to provide a galvanometer assembly, including one or both of its anchoring members, which can be assembled, adjusted and tested completely before installation and which can then be installed as a unit in its barrel with a minimum of further adjustment.

Another important object is to provide a galvanometer of simple design and inexpensive construction, which is of small size and high sensitivity, and which is readily adapted to mass production.

Another important object is to provide a galvanometer which is capable of being damped to a high degree by electrical means.

An additional object is to provide a totally enclosed barrel-type galvanometer which is completely sealed against the entry of water and dust.

A more specific object is the provision of a totally enclosed, barrel-type galvanometer having a novel form of anchoring member for frictionally locking an end of the vibratory element to the interior of the barrel.

Other and more specific objects of this invention will appear from the following description and from the accompanying drawings in which—

Fig. 1 is a sectional elevation of a galvanometer assembly in accordance with one embodiment of this invention;

Fig. 2 is a sectional elevation of a galvanometer assembly in accordance with another embodiment of this invention; and

Fig. 3 is a detail of the galvanometer of Fig. 2 viewed along line 3—3 of Fig. 2.

Referring to the drawing and to Fig. 1 in particular, the numeral 10 designates a galvanometer barrel made of non-magnetic material such as brass. The external diameter of the upper portion of the barrel is slightly larger than that of the lower portion which fits snugly into a circular hole 11 in the pole piece structure of the magnet assembly. The latter comprises the pole pieces 12 and 13, the "Alnico" magnets 14 and 15

3

and the base plate 16. The pole pieces 12 and 13 and base plate 16 are made of high permeability magnetic material such as soft iron. The upper pole piece assembly, as shown in Fig. 3 is made up of three pieces, the two magnetic pole pieces 12 and 13 and the intermediate strip 44 of non-magnetic material. These three pieces are normally brazed together to form a rigid unit, after which holes 11 are bored to receive the several galvanometer units normally employed in instruments such as seismograph oscillograph cameras.

The vibratory element of the galvanometer assembly comprises the coil 18 wound upon two insulating beads 19-19 and supported between two current conducting suspension fibers 20 and 21. These fibers are looped through the central holes of the beads that form the end structure of the coil and are soldered. The lower suspension fiber 20 is soldered into an anchor screw 22 which forms an anchoring member for the lower end of the vibratory element. The shaft of screw 22 passes through the bore of an insulating bushing 23 which fits snugly into the lower end of the barrel 10 and is provided with an annular shoulder 23a which rests against the lower end of the barrel. Screw 22 is anchored to the end of the barrel by means of a lock nut 24 and a second nut 25 which is adapted to make electrical contact with the free end of a spring contact 26. The other end of the latter is supported on an L-shaped insulating block 27 which is mounted by attachment to the inner faces of pole piece 12 and magnet 15 at their juncture. The two ends of coil 18 are brought out and connected at 17 and 17a to the respective suspension fibers 20 and 21. A current lead 26b is connected to contact 26 and a ground lead 27b is connected to a binding screw 27a which extends through insulating block 27 and into pole piece 12.

The upper end of suspension fiber 21 is formed into a loop and soldered to the bail 31a of a coil spring 31 which is suspended from a square block 33. Block 33 is adapted to slide in square ways 33a formed in the upper portion of barrel 10 below an internally threaded section 35 of the barrel. A set screw 32 is mounted in the side of barrel 10 and is arranged to engage block 33. The latter is adapted to be moved longitudinally along ways 33a by means of a threaded screw 34 which carries a depending spherical head 34a which is rotatable by screw 34 in a spherical recess 34b arranged in block 3. Screw 34 is provided with a kerf 34c in its upper end for insertion of a screw driver or other suitable tool when it is desired to turn screw 34. A cap screw 36 having a wrench square 36a in the top thereof is inserted in the threaded portion 35 of the barrel above the screw 34.

A mirror 29 is cemented to the upper suspension fiber 21 just above coil 18 and serves to indicate the vibratory motion of the coil. A window 30 is set in an opening in the side of barrel 10 to admit light from a conventional galvanometer lamp to the mirror and to transmit the reflected light to the film or sensitized paper in the usual manner. Mirror 30 is preferably set at an angle to prevent reflections from its outer surface from reaching the film or sensitized paper.

With the parts in the form described, the entire vibratory element including coil 18, suspension fibers 20 and 21, and mirror 29, together with the upper anchoring member, comprising screw 34, its connected block 33 and coil spring 31, and the lower anchoring member, comprising screw 22, may be completely assembled outside barrel

4

10 in a suitable jig or fixture and thoroughly tested and adjusted to the desired characteristics and matched with other similar galvanometers to be used in the same group.

5 The assembly of the galvanometer is then completed in the following manner: Insulating bushing 23 is inserted in the lower end of barrel 10 in which it fits tightly. The entire vibratory element assembly described above is then inserted 10 into the barrel through the upper end, thereof, screw 34 engaging threads 35 and being screwed down therein until block 33 is engaged in ways 33a. The shaft of anchor screw 22 is passed through the bore of insulating bushing 23 and nuts 24 and 25 applied to the end thereof to tightly 15 anchor the vibratory element assembly to the lower portion of the barrel and to seal the same against the entry of moisture and dust. Coil 18 will then be properly positioned in the barrel between pole pieces 12 and 13, and mirror 29 will come opposite window 30. Screw 34 will then be turned to adjust block 33 at a position along ways 33a to apply the desired degree of tension to the vibratory element. Set screw 32 will then be tightened to lock block 33 in the adjusted position. 20 Thereafter, cap screw 36 will be screwed into the upper end of the barrel and thus tightly seal the upper end of the barrel against the entry of moisture or dust into the barrel. By application of a suitable tool to wrench square 36a the barrel may be turned to focus the light beam reflected from mirror 29 at the desired point on the film or sensitized paper (not shown).

With this type of assembly, it will be seen that 25 the entire vibratory element and its anchoring members may be inserted as a unit and the only adjustment required after installation of the unit in the barrel will be the longitudinal adjustment of block 33 to apply the desired degree of tension to the vibratory element. This desired degree of 30 tension may even be predetermined at the time the structure is assembled before installation in the barrel, so that it is only necessary to adjust block 33 to an indicated position in the ways 33a which will produce the pre-determined degree of 35 tension to the vibratory element. The assembly will be entirely sealed against entry of dirt, dust and moisture and is readily adapted for the use of an atmosphere of inert gas inside the barrel if 40 desired.

Fig. 2 illustrates another embodiment in accordance with this invention which is particularly adapted for the manufacture of high frequency galvanometers. This is accomplished by installing 45 pole piece inserts in the barrel opposite the pole pieces, to thereby reduce the air gap and increase the flux density which permits a high degree of electrical damping of the coil. The coil dimensions may then be greatly reduced to produce 50 a vibratory element of as high a frequency as desired. However, the use of pole piece inserts constricts the bore of the barrel and the constriction may be of such degree in the case of high frequency galvanometers as to prevent the passage 55 of the lower anchoring member through the barrel, unless its lateral dimensions are reduced to a degree which will weaken it too greatly for maintaining the desired degree of tension on the vibratory element.

60 Fig. 2 illustrates an embodiment which overcomes these disadvantages in the construction of a high frequency galvanometer. In this embodiment pole piece inserts 37-37 are inserted in barrel 10 opposite pole pieces 12 and 13 and in tight frictional contact therewith. The 65

thickness of pole-piece inserts 31-37 are such as to provide an air gap therebetween of the desired dimensions. Fig. 3 illustrates the relative positions of the pole-piece inserts and coil 18. All the other elements of the galvanometer assembly, except for the lower anchoring member are identical with those illustrated in Fig. 1 and the identical parts bear the same identifying numerals in both figures.

The modified form of the lower anchoring member comprises a screw 38 having a smooth, downwardly tapering conical section 39 which terminates in a straight, threaded shaft 40. An insulating bushing 41, provided with an annular shoulder 42 adapted to bear against the end of barrel 10 is dimensioned to slip loosely into the lower end of barrel 10. The inner end portion of bushing 41 is provided with a conical bore 43 having a taper substantially complementary to that of tapered section 39 of the screw 38 and the bore of the outer end portion of bushing 41 is of substantially uniform diameter to accommodate threaded shaft 40.

In constructing a galvanometer employing pole-piece inserts which are spaced too closely to permit passage of the lower anchoring member therebetween. The assembly using the modified lower anchoring member is accomplished in the following manner:

The entire vibratory element assembly is made up before installation in the barrel and completely tested and adjusted as previously described. However, upper suspension fiber 21 is detachably connected to bail 31a of the upper anchoring member by looping the end of the fiber so that it may be hooked over the bail. The lower suspension fiber 20 is permanently soldered to the head of anchor screw 38. After the assembly is tested and adjusted as desired, the loop at the upper end of suspension fiber 21 is detached from bail 31a and the remainder of the vibratory element assembly, comprising suspension fiber 21, mirror 29, coil 18, lower suspension fiber 20 and anchor screw 38 are inserted into barrel 10 through the lower end thereof. This assembly is drawn through the barrel until the loop in suspension fiber 21 appears at the upper end of the barrel, whereupon it is attached to bail 31a and is ordinarily soldered thereto. The assembly is then retracted through the barrel and screw 34 engaged with threads 35 and screwed down until threaded shaft 40 of screw 38 appears at the lower end of the barrel. Insulating bushing 41 is then slipped over the shaft end of screw 38 and inserted in the end of the barrel. Nuts 24 and 25 are then screwed on the threaded shaft and tightened. The tightening of nuts 24 and 25 draws conical section 39 of the screw into the tapered bore of insulating bushing 41 and the resulting compression on the tapered bore of the bushing causes the bushing to expand laterally into tight frictional engagement with the inner wall of barrel 10. This firmly locks the lower end of the vibratory element to the barrel and at the same time tightly seals the lower end of the barrel. Screw 34 is then adjusted in the manner previously described to apply the desired degree of tension to the vibratory element and set screw 32 tightened to fix the position of block 33. Cap screw 36 is inserted in the upper end of the barrel to complete the assembly.

It will be evident that the tapered form of anchoring member illustrated in Fig. 2 may be employed in place of anchor screw 22 and its complementary bushing 23 in a galvanometer of

the form illustrated in Fig. 1 with equally satisfactory results. In such event, however, upper suspension fiber 21 may be permanently connected to bail 31a before installation of the vibratory element in the barrel.

It will be recognized that various alterations and modifications may be made in the details of the structure herein described without departing from the scope of the appended claims but within the spirit of this invention.

What I claim and desire to secure by Letters Patent is:

1. A totally enclosed galvanometer of the barrel type, comprising a cylindrical barrel and a vibratory element mounted therein, said vibratory element having an anchoring member connected to each end thereof adapted to form closures for the opposite ends of said barrel, said vibratory element and both of said anchoring members being insertable into said barrel through one end thereof in fully assembled form, and means for locking said anchoring members to opposite ends of said barrel.

2. A totally enclosed galvanometer of the barrel type, comprising a cylindrical barrel and a vibratory element mounted therein, said vibratory element having an anchoring member connected to each end thereof adapted to form closures for the opposite ends of said barrel, said vibratory element and both of said anchoring members being insertable into said barrel through one end thereof in fully assembled form, and means for locking said anchoring members to opposite ends of said barrel, one of said anchoring members having a tapered portion compressively engageable with its associated locking means for expanding the latter into frictional engagement with the interior of said barrel.

3. A totally enclosed galvanometer of the barrel type, comprising a cylindrical barrel and a vibratory element mounted therein, said vibratory element having an anchoring member connected to each end thereof adapted to form closures for the opposite ends of said barrel, said vibratory element and both of said anchoring members being insertable into said barrel through one end thereof in fully assembled form, means for locking said anchoring members to opposite ends of said barrel, one of said anchoring members having a tapered portion compressively engageable with its associated locking means for expanding the latter into frictional engagement with the interior of said barrel, and the other of said anchoring members having threaded engagement with the opposite end of said barrel.

4. A totally enclosed galvanometer of the barrel type, comprising a cylindrical barrel and a vibratory element mounted therein, said vibratory element having an anchoring member connected to each end thereof adapted to form closures for the opposite ends of said barrel, said vibratory element and both of said anchoring members being insertable into said barrel through one end thereof in fully assembled form, means for locking said anchoring members to opposite ends of said barrel, one of said anchoring members having a tapered portion compressively engageable with its associated locking means for expanding the latter into frictional engagement with the interior of said barrel, the other of said anchoring members having threaded engagement with the opposite end of said barrel and adjustable longitudinally therein, and supplemental means for locking said last-

mentioned anchoring means in the adjusted position.

5. A totally enclosed galvanometer of the barrel type, comprising a cylindrical barrel and a vibratory element mounted therein, said vibratory element having an anchoring member connected to each end thereof adapted to form closures for the opposite ends of said barrel, said vibratory element and both of said anchoring members being insertable into said barrel through one end thereof in fully assembled form, means for locking said anchoring members to opposite ends of said barrel, one of said anchoring members having a tapered portion compressively engageable with its associated locking means for expanding the latter into frictional engagement with the interior of said barrel, the other of said anchoring members having threaded engagement with the opposite end of said barrel, and an additional closure member for said opposite end of said barrel.

6. A totally enclosed galvanometer of the barrel type, comprising a cylindrical barrel and a vibratory element mounted therein, said vibratory element having a first anchoring member detachably connected to one end thereof and a second anchoring member permanently connected to the opposite end thereof, means for locking said second anchoring member to said barrel, and means carried by said second anchoring member and cooperating with said locking means to effect frictional engagement of said locking means with the interior of said barrel.

7. A totally enclosed galvanometer of the barrel type, comprising a cylindrical barrel and a vibratory element mounted therein, said vibratory element having a first anchoring member detachably connected to one end thereof and a second anchoring member permanently connected to the opposite end thereof, means for locking said second anchoring member to said barrel, said second anchoring member having a tapered portion compressively engageable with said locking means for expanding the latter into frictional engagement with the interior of said barrel.

8. A totally enclosed galvanometer of the barrel type, comprising a cylindrical barrel having an internally threaded portion at one end thereof, a vibratory element mounted in said barrel, first and second anchoring members, said first anchoring member being detachably connected with one end of said vibratory element and in threaded engagement with said threaded portion of said barrel, said second anchoring member being permanently connected to the opposite end of said vibratory element, means for locking said second anchoring member to said barrel, said means including a tapered member carried by said second anchoring member and compressively engageable with said locking means to expand the latter into frictional engagement with the interior of said barrel, and a supplemental closure member mounted in the outer end of said threaded portion of said barrel.

9. A totally enclosed galvanometer of the barrel type, comprising a cylindrical barrel having a constriction in an intermediate portion of the bore thereof, a first anchoring member mounted in the bore at one end of said barrel, a vibratory element mounted in the barrel and extending through said constricted portion, said vibratory element being detachably connected at one end to said first anchoring member, a second anchoring member permanently connected to the

opposite end of said vibratory element and insertable therewith through the opposite end of said barrel, means for locking said second anchoring member to said barrel, and means carried by said second anchoring member and cooperating with said locking means to effect frictional engagement of said locking means with the interior of said barrel.

10. A totally enclosed galvanometer of the barrel type comprising, a cylindrical barrel having a constriction in an intermediate portion of the bore thereof, a first anchoring member mounted in the bore at one end of said barrel, a vibratory element mounted in the barrel and extending through said constriction, said vibratory element being detachably connected at one end to said first anchoring member, a second anchoring member permanently connected to the opposite end of said vibratory element and insertable therewith through the opposite end of said barrel and means for locking said second anchoring member to said barrel, said second anchoring member having a tapered portion compressively engageable with said locking means for expanding the latter into frictional engagement with the interior of said barrel.

11. In a totally enclosed galvanometer of the barrel type which includes a cylindrical barrel having a constriction in an intermediate portion of the bore thereof and a vibratory element mounted in said barrel and extending through said constriction, means for anchoring said vibratory element to the opposite ends of said barrel comprising, a first anchoring member mounted in one end of said barrel and detachably connected to one end of said vibratory element, a second anchoring member permanently connected to the opposite end of said vibratory element and insertable therewith through the opposite end of said barrel, means for locking said second anchoring member to the opposite end of said barrel, and means carried by said second anchoring member and cooperating with said locking means to effect frictional engagement of said locking means with the interior of said barrel.

12. In a totally enclosed galvanometer of the barrel type, which includes a cylindrical barrel having a constriction in an intermediate portion of the bore thereof and a vibratory element mounted in said barrel and extending through said constriction, means for anchoring said vibratory element to the opposite ends of said barrel comprising, a first anchoring member mounted in one end of said barrel and detachably connected to one end of said vibratory element, a second anchoring member permanently connected to the opposite end of said vibratory element and insertable therewith through the opposite end of said barrel, and means for locking said second anchoring member to the opposite end of said barrel, said second anchoring member having a tapered portion compressively engageable with said locking means for expanding the latter into frictional engagement with the interior of said barrel.

13. In a totally enclosed galvanometer of the barrel type, which includes a cylindrical barrel having a constriction in an intermediate portion of the bore thereof and a vibratory element mounted in the barrel and extending through said constriction, means for anchoring said vibratory element to the opposite ends of said barrel comprising a first anchoring member screwed into one end of the barrel and detachably

connected to one end of the vibratory element, and a second anchoring member permanently connected to the opposite end of said vibratory element and adapted to be anchored to the interior of the opposite end of said barrel by frictional engagement therewith.
